(57) **CLAIM**

The ornamental design for a cultivator, as shown and described.

DESCRIPTION

FIG. 1 is a top, front and left perspective view of a cultivator showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a partial enlarged view of portion 8 shown in FIG. 2.

The dash-dash broken lines in the drawings depict portions of the cultivator that form no part of the claimed design. The dot-dash broken lines in the drawings depict the boundaries of the partial enlarged views that form no part of the claimed design.

1 Claim, 8 Drawing Sheets
